(57) **CLAIM**

The ornamental design for a footwear heel as shown and described.

DESCRIPTION

1. Footwear heel

1.1 is a side view of a footwear heel, showing the new design;

1.2 is a perspective view thereof;

1.3 is an opposite side view thereof;

1.4 is a bottom view thereof;

1.5 is a top view thereof;

1.6 is a front view thereof; and

1.7 is a rear view thereof.

The broken lines show environmental structure in the form of a footwear upper and sole as well as portions of the footwear heel that form no part of the claimed design.
